UNITED STATES PATENT OFFICE.

JOHN P. ANDERSON AND JOHN F. MILLER, OF SARANAC, MICHIGAN.

WASHING-MACHINE.

SPECIFICATION forming part of Letters Patent No. 427,031, dated May 6, 1890.

Application filed February 12, 1890. Serial No. 340,111. (No model.)

To all whom it may concern:

Be it known that we, JOHN P. ANDERSON and JOHN F. MILLER, citizens of the United States, residing at Saranac, in the county of 5 Ionia and State of Michigan, have invented certain new and useful Improvements in Washing-Machines; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 Our invention relates to that class of washing-machines in which there is a vibrating rubber, by means of which the clothes to be washed are subjected to a combined rubbing and squeezing action.

20 The object of our invention is to construct a washing-machine which, while thoroughly effective as a washer, will be so simple in construction that it can be made at a low cost, and that can be so easily operated that it will 25 save much labor. The manner in which we secure a washing-machine combining these advantages is more fully described hereinafter and illustrated in the accompanying drawings, in which—

30 Figure 1 is a longitudinal sectional view. Fig. 2 is a detail view in perspective of the means for holding the rubber shaft in position.

In our improved washing-machine, A represents the bottom and ends, made of one 35 continuous piece of heavy zinc or other non-corroding metal, and having formed throughout a portion of its length a series of transverse corrugations. To the sides B, which, 40 with the bottom and ends, constitute the suds-box of the machine, are fixed the legs a. In suitable bearings b in the sides B rest the horizontal shaft C, from which is suspended by the slotted hangers c the rubber D. This 45 rubber conforms in outline to the shape of the suds-box, and consists of the corrugated bottom d, the sides e, and brace f. Extending to the bottom d of the rubber through suitable holes in the center of the shaft C and 50 the brace f is a vertical rod E, to the upper end m of which is pivoted the lever-handle F.

To this handle, at a point about half-way between pivot m and its outer end, is pivoted a supporting-rod g, which, as will be seen, acts as a fulcrum for the handle, and the lower 55 end of which terminates in a hook h, which engages with an eye or staple i in the end of the box.

Encircling the rod E, and between the bearings formed by the shaft C and the brace f, 60 is a spiral spring s. To the sides of the suds-box are fastened hooks m, which when in use engage the projecting ends of the shaft C, and thus retain it in place when the machine is 65 being operated.

The manner of operating our improved washing-machine will be apparent from its simple construction. Its advantages are, in addition to the cheapness of construction attained by the few parts used, the uniform 70 yielding capacity of the rubber, which is effected by the single spiral spring arranged around the rod and in fixed bearings, so that it cannot work loose or get out of line, and in the fact that said spring is always in direct 75 line with the point of greatest pressure on the rubber, and in the great power secured by the handle working as a lever to either raise or lower the rubber. It will be seen that when the clothes have been rubbed sufficiently they 80 may be drawn to the end of the tub away from the free end of the handle, and by pulling upon the latter the rubber will be pressed against the clothes, and thus squeeze out the 85 surplus moisture.

Having described our invention, what we claim as novel, and desire to cover by Letters Patent, is—

In a clothes-washing machine, the combination of the suds-box, having a bottom of 90 corrugated sheet metal, with the oscillating rubber having a corrugated bottom, slotted hangers, and brace f, and the shaft C, rod E, spring s, and handle F, substantially as described.

In testimony whereof we affix our signatures in presence of two witnesses.

JOHN P. ANDERSON.

JOHN F. MILLER.
